Primary Examiner — Samantha Q Lawrence(74) *Attorney, Agent, or Firm* — Harness, Dickey & Pierce, P.L.C.; Anthony G. Fussner(57) **CLAIM**

The ornamental design for orthopedic leg brace for pets, as shown and described.

DESCRIPTION

1.-2. Orthopedic leg brace for pets

Figure 1.1 is a perspective view of a first embodiment of an orthopedic leg brace for pets;

Figure 1.2 is another perspective view thereof;

Figure 1.3 is a rear perspective view thereof;

Figure 1.4 is a front view thereof;

Figure 1.5 is a side view thereof;

Figure 1.6 is a rear view thereof;

Figure 2.3 is a rear perspective view thereof;

Figure 2.4 is another perspective view thereof;

Figure 2.5 is a side view thereof;

Figure 2.6 is a front view thereof; and

Figure 2.7 is another perspective view thereof.

The broken lines which illustrate the pet shown in Figures 1.1-2.7 illustrate environment of the orthopedic leg brace for pets that form no part of the claimed design.

The broken lines shown on the claimed design in Figures 1.1-2.7 illustrate stitching on the surface of the orthopedic leg brace for pets and form no part of the claimed design. The surface underneath the stitching is claimed.
